UNITED STATES PATENT OFFICE.

FRANK W. WATERMAN, OF BALTIMORE, MARYLAND.

STEAM-MOTOR FOR AUTOMOBILES.

SPECIFICATION forming part of Letters Patent No. 659,162, dated October 2, 1900.

Application filed December 14, 1899. Serial No. 740,343. (No model.)

To all whom it may concern:

Be it known that I, FRANK W. WATERMAN, a citizen of the United States, residing at Baltimore, in the State of Maryland, have 5 invented new and useful Improvements in Steam-Motors for Automobiles or other Vehicles, of which the following is a specification.

My invention relates to certain new and useful improvements in steam-motors for automobiles or other vehicles.

My invention has for its main object to provide, in connection with mechanism operated by a single eccentric on the main shaft for controlling the valves of a high and a low pressure cylinder, novel mechanism for affording a variable cut-off for the high-pressure cylinder, while permitting the cut-off of the valves of the low-pressure cylinder to remain constant, the purpose being to enable 15 the maximum expansive power of the steam to be utilized in the low-pressure cylinder at all times, so that the exhaust-steam passing therefrom to the condenser will have the minimum pressure.

Other objects of the invention relate to features of construction, combination, or arrangement of parts and principles of operation hereinafter fully described, and particularly pointed out in the claims.

I have illustrated the invention in the accompanying drawings, in which—

Figure 1 is a view in elevation of my improved motor, taken on a line at right angles to the drive-shaft, the high-pressure cylinder 35 and part of the frame being in section. Fig. 2 is a view taken on the line 2 2 of Fig. 1 and viewed in the direction of the arrow. Fig. 3 is an edge view of a rock-arm and parts connected therewith for varying its throw and 40 controlling its motion. Fig. 4 is a sectional view of the eccentric mechanism. Fig. 5 is a view on the line 5 5 of Fig. 4. Fig. 6 is a detail view of a plate adapted to be connected with the eccentric-ring, and Fig. 7 is a perspective view of a valve-plug.

Referring to the drawings, the numeral 1 indicates the high-pressure cylinder, and 2 the low-pressure cylinder, and the numerals 3 and 4 indicate, respectively, the steam-chests 50 of the two cylinders. The cylinders are arranged in the inclined positions shown in Fig. 1 and on opposite sides of and in operative re-

lation with a common crank-shaft 5. On opposite sides of the lower end of each cylinder are cast integral lugs 6, which receive the upper ends of pillars 7, which support the cylinder. The lower ends of these pillars are supported on integral extensions 8 of the framing 9 of the motor. The lugs 6 and extensions 8 also support between them guide-rods 10. 60 In Fig. 2 I have illustrated this construction in connection with the low-pressure cylinder 2; but it will be understood that the cylinder 1 is supported in a similar manner and is provided with similar guide-rods. These guide-rods are for the cross-heads to work on. The piston-rod of the low-pressure cylinder is indicated by the numeral 11, its cross-head by 12, and the pitman by 13, which pitman at its outer end is connected with the crank 14 of 70 the shaft 5. The piston-rod of the high-pressure cylinder is indicated by 15, its piston by 16, its cross-head by 17, and its pitman by 18, which pitman at its outer end is connected with said crank 14 on shaft 5. The shaft 5 is 75 rotatably supported in suitable hangers 20.

The numeral 21 indicates the steam-inlet pipe to the high-pressure cylinder, and 22 23 the exhaust-pipes leading therefrom, which exhaust-pipes communicate, as usual, with a 80 common steam-inlet pipe 24, leading into the low-pressure cylinder.

The numerals 25 26 indicate the exhaust-pipes leading from the low-pressure cylinder to the condenser, which latter, however, is 85 not shown.

Each steam-chest 34 is provided with a central steam-chamber 27, communicating at opposite ends, through the medium of ports 28 29, with valve-chambers 30 31, which in turn 90 communicate, through ports 32 33, with the exhaust-pipes 22 23. Located in each valve-chamber is a valve, said valves being indicated, respectively, by the numerals 34 35, and controlling-ports 36 37, leading, respectively, into opposite ends of the cylinder. The valves 34 35 are of the "plug" type of valve and have the general construction illustrated in Fig. 7.

The numeral 38 indicates the body of the 100 valve, which is hollow and slightly tapered from one end to the other, and the numeral 39 the valve-stem. The valve body or shell is provided on opposite sides with flattened

portions 40 41 and in the bottom of the valve or side covering-port 36 or 37, adjacent to the side 41, with an elongated opening 42. This leaves a portion of the bottom of the valve-shell to operate as a cut-off for the port 36 or 37, said portion being indicated by the numeral 43. The flattened side 41 is provided throughout its length, along its upper edge portion, with an opening 44, which is approximately about one-half the width of the flattened portion 41. The valves 45 46 of the low-pressure cylinder are the same in construction and operation as those of the high-pressure cylinder, so that a description of one set of valves will suffice for both.

I will now describe the operation of the valves of the high-pressure cylinder, referring to Fig. 1, wherein said cylinder is shown in section at the right of the figure. In the position of the parts there shown the piston 16 has started on its forward movement, and steam is passing from the chamber 27, through port 29, into the valve-chamber 31, and thence through the opening 44 into the interior of valve 35, whence it passes out through the opening 42 of said valve and through port 37 into the rear end of cylinder 1. At the front end of the cylinder steam is exhausting through port 36, which is partly uncovered by the cut-off 43, past the straight side 40 of valve 34, and through port 32 to the exhaust-pipe 23. When the piston has reached the limit of its forward movement, the cut-off mechanism, hereinafter described, operates to reverse the positions of the valves, so that the valve 34 will occupy the same relative position now occupied by valve 35, while the latter valve will occupy the same relative position now occupied by valve 34. In this reversed position of the valves the steam will enter cylinder 1 through valve 34 in the same manner as described with reference to valve 35, while at the rear end of the cylinder the steam will exhaust past the flat side 40 of valve 35 into the exhaust-pipe 22. When either valve 34 or 35 is in the position to admit steam into the cylinder, which is the position shown with respect to valve 35, communication with the exhaust-port 32 or 33, as the case may be, is cut off by reason of the fact that the cut-off 43 of the valve then occupies a position between the exhaust-port and the port 36 or 37, so that the full expansive power of the steam can be utilized in the low-pressure cylinder. From the above construction it will be seen that the exhaust-steam from the high-pressure cylinder passes alternately through the pipes 22 and 23 into the common inlet-pipe 24, leading to the steam-chest 4 of the low-pressure cylinder, in which cylinder the same operation of the valves 45 46 takes place as described with reference to the valves 34 35, except that the steam passes from the cylinder 1 through the pipes 25 26 to the condenser. Upon the valve-stem 39 of each valve is firmly secured a lever-arm 47, the lever-arms of each cylinder being pivotally connected at

their outer ends by a connecting-rod 48. This mechanism is shown only in connection with the valves of the low-pressure cylinder in Figs. 1 and 2; but similar mechanism is employed for operating the valves of the high-pressure cylinder. Pivotally connected to the innermost lever-arm 47 of each pair is a valve-rod, the valve-rod of the low-pressure cylinder being indicated by the numeral 49 and that of the high-pressure cylinder by the numeral 50. As shown in Fig. 2, the connection of the valve-rod is not directly with the lever-arm 47, but with a pin 51, carried by said lever-arm. The means for reciprocating the valve-rods 49 50, so as to cause the valves to be rocked back and forth through the medium of the connected lever-arm 47, secured on the stems of the valves, will now be described, such means constituting what has been termed herein the "variable cut-off mechanism."

The numeral 52 indicates an eccentric-ring having an elongated aperture 53, by which means it is mounted and vertically movable on the shaft 5. Said ring is also provided on opposite sides, respectively, of the central aperture 53 with two elongated slots 54. Extending along one side of the shaft for a considerable distance is a feather 55. Mounted on the shaft 5, on opposite sides, respectively, of the eccentric-ring 52, are two circular plates 56 57, one of which, 56, is shown in detail in Fig. 6. These plates are each provided with a central opening 58, by means of which they may be inserted on the shaft, and with a groove 59, leading from said opening for receiving the feather 55. On opposite sides of the central opening 58 each plate is provided on its inner side with studs 60, two in number, which when the plates are secured on opposite sides of the eccentric-ring 52 are designed to enter the slots 54. As the shaft 5 revolves the plates 56 57, being keyed thereon, will revolve with it and through the medium of the studs 60 will cause the eccentric-ring 52 to revolve. The slots 54 are free to slide over the stud 60, and by adjusting the eccentric-ring vertically on the shaft 5, which adjustment is permitted by the elongated aperture 53, the throw of the eccentric can be varied. The bottom wall of the aperture 53 is recessed, as indicated at 61, to receive the feather 55 when the ring has been adjusted to bring this end of the aperture against the shaft 5, so that the ring may be adjusted to the fullest extent in this direction. The means for adjusting the eccentric-ring will now be described.

Keyed on the shaft 5, through the medium of the feather 55 at one side of the eccentric, is a cylindrical block 62, having a circumferential groove 63 and having its end portion farthest removed from the eccentric tapered or inclined, as indicated at 64. Near the outer edge of the eccentric, on the side adjacent to the block 62, are provided two apertured lugs or ears 65, between which is piv-

totally secured, by means of a pin 66, the end of a link 67, the opposite end of which is pivotally secured by a pin 68 near the bottom of a radial slot 69, formed in the outer edge portion of the block 62 in the end adjacent to the eccentric. The plate 56, which is the one adjacent to said block, is provided with a similar slot 70 in line with the link 67. These slots allow for the play of the link in the movement of the block 62, as presently described.

The numeral 71 indicates an upright lever-arm having a bifurcated portion 72 about centrally of its length, embracing a stud 73, 15 projecting upward from the framing 9 and pivotally secured thereon by a pin 74. Below the point of pivotal connection 74 the two arms of the bifurcation are extended outward in opposite directions at right angles to the lever-arm, as indicated at 75, and are then extended downward to form two parallel forks 76, embracing the block 62, each fork having at its outer end an inwardly-extending stud 77, engaging in the circumferential groove 63 of said block, but permitting its free revolution. By moving the upper end of the lever-arm 71 outward or in a direction away from the cylinders the block 22, by reason of the engagement of the studs 77 in the slot 63 thereof, will be moved inward or toward the eccentric, and the link 67 as its lower end is carried inward thereby will raise the eccentric-ring 52 a greater or less distance, according to the distance the 25 block 62 is moved inward, such movement increasing the throw of the eccentric, as will more clearly appear from Figs. 4 and 5. The slots 69 and 70 permit the movement of link 67 in a direction toward a vertical line, as will be seen from Fig. 4. The extreme inward movement of block 62 will raise the eccentric-ring 52 to the limit of its adjustment in this direction, in which position the feather 35 will lie in the groove 61. The movement 40 of lever-arm 71 in the opposite direction to that just described will lower the eccentric-ring 52 and decrease the throw of the eccentric, as will be understood. Pivotally secured on the outer end of the lever-arm 71 is 45 a rod 78 for moving said lever-arm. Any suitable means may be employed in connection with the rod 78 to hold it firmly in the adjusted position to which it may be moved.

The numerals 79 80 indicate, respectively, 50 two eccentric-straps mounted on the eccentric-ring 52 in the usual manner. Formed integral with the eccentric-strap 80 is a lug 81, suitably apertured and recessed to have secured therein, by nuts or the like, the lower 55 end of the valve-rod 50, which operates the valves of the high-pressure cylinder, as previously described. It will thus be seen that by varying the throw of the eccentric in the manner previously described I thereby vary 60 the throw or extent of reciprocation of the valve-rod 50, and consequently vary the cut-off of the valves 34 35. On the opposite ec-

centric-strap 79 is provided an integral arm 82, and the mechanism connected and co-operating therewith for operating the valve-rod 70 49, so that said valve-rod may be operated from the eccentric 52, while the variations in adjustment of the eccentric shall not affect the cut-off of the valves 45 46, will now be described.

The numeral 83 indicates a bracket constituting an extension of the frame 9 and having a bracket-arm 84, in which is slidably mounted a guide-block 85. Pivotally connected to the inner end of this guide-block, 80 at one side thereof, is a long arm 86, the outer end of which is pivotally connected at 86^a to the outer end of a crank-arm 87, the lower end of which crank-arm is fast on a shaft 88, mounted in bearings 89 on the hangers 20. 85 Secured on the shaft is one end of a curved arm 89^a, the outer end of which is bifurcated and has rotatably mounted in such bifurcated portion a beveled roller 90, which is held constantly in contact with the inclined surface 90 64 of the block 62 by means of a coiled spring 91, one end of which is secured to the crank-arm 87 and the other end to the frame of the machine, as shown in Fig. 1.

The numeral 92 indicates a rock-arm which 95 is pivotally secured at its lower end to the outer end of the guide-block 85 on the opposite side to that on which the lever-arm 71 is pivoted. A single pivot-pin 93, passed through the end of said guide-block, serves for pivoting said lever-arm and the rock-arm 92. Toward its outer end the rock-arm 92 is provided with a slot 94 and at its extreme outer end is pivotally connected at 95 to a head 96, which in turn is secured on the lower end 100 of the valve-rod 49. Pivotally mounted on the bracket 83 at 83^a is a crank-arm 97, having a pin 98, extending through and working in the slot 94 of the rock-arm 92. To this pin the arm 82 of eccentric-strap 79 is pivotally connected. The crank-arm 97 will be rocked back and forth in the revolution of eccentric-ring 52 by reason of the pivotal connection of its pin 98 with the arm 82 of eccentric-strap 79. As the pin 98 also works 115 in slot 94 of the rock-arm 92, said rock-arm in the revolution of the eccentric will thereby be swung back and forth on the pivot 93.

The operation of this mechanism is as follows: As the block 62 is moved by the lever-arm 71 toward the eccentric to raise the ring 52, and thereby increase the throw of the eccentric, which will accordingly increase the throw of the valves 34 35 of the high-pressure cylinder, the spring 91 will pull the crank-arm 87 downward, which movement of the crank-arm through the medium of the arm 86 will move the guide-block 85 outward, carrying with it the rock-arm 92, so that the pin 98, which in the position of the parts shown in Figs. 1 and 3 is near the bottom of the slot 94 of said rock-arm, will now occupy a position nearer the upper end of said slot, so that while the arc of movement of

pin 98 has been increased the corresponding or proportionate decrease in distance between the pin 98 and the outer end of the rock-arm will prevent any increase in the throw of said rock-arm. Should the block 62 be moved outward or away from the eccentric to decrease the throw thereof and the throw of the valves 34 35, the roller 90 as it rides up the incline 64 will force the curved arm 89 outward, thereby revolving shaft 88 and raising crank-arm 87, which movement through the medium of the arm 86 will cause the rock-arm 92 to be raised, the slot 94 riding over the pin 98, so that said pin will now occupy a position nearer the bottom of said slot, and the distance from the pin 98 to the outer end of the rock-arm will be increased in proportion to the decrease in throw of the eccentric and the throw of rock-arm 92 remains uniform. The guide-block 85 serves as an adjustable pivot-bearing for the arm 86 and rock-arm 92 and is of course stationary after the adjustment has once been made.

It will be seen from the above construction that no matter what variation may be effected in the throw or cut-off of valves 34 35 the cut-off of the valves 45 46 will remain uniform, so that the full expansive power of the steam exhausted from the high-pressure cylinder can be utilized in the low-pressure cylinder and the maximum pressure of the steam be employed. Owing to the very low pressure of the steam leaving the low-pressure cylinder I contemplate after passing the steam through a condenser accomplishing the final exhaust thereof to the air without the formation of vapor.

It will be obvious without further specification that I can utilize the adjustment of the eccentric for the purpose of reversing the engine.

Having thus fully described my invention, what I claim as new is—

1. In a steam-motor, in combination with a high-pressure and a low-pressure cylinder geared to a common drive-shaft, an eccentric mounted on said shaft having straps, a valve-rod for operating the valves of the high-pressure cylinder connected directly to one of said straps, a valve-rod for operating the valves of the low-pressure cylinder, and differential cut-off mechanism connecting said latter valve-rod with the other of said eccentric-straps, substantially as described.
2. In a steam-motor, in combination with a high-pressure and a low-pressure cylinder geared to a common drive-shaft, an eccentric mounted on said shaft having straps, a valve-rod for operating the valves of the high-pressure cylinder connected directly to one of said straps, a valve-rod for operating the valves of the low-pressure cylinder, differential cut-off mechanism connecting said latter valve-rod with the other of said eccentric-straps, and means for varying the throw of said eccentric, substantially as described.

3. In a steam-motor, in combination with a high-pressure and a low-pressure cylinder, geared to a common drive-shaft, an eccentric mounted on said shaft having straps, a valve-rod for operating the valves of the high-pressure cylinder connected directly to one of said straps, a valve-rod for operating the valves of the low-pressure cylinder, differential cut-off mechanism connecting said latter valve-rod with the other of said eccentric-straps, means for varying the throw of said eccentric and mechanism operated thereby to vary the throw of said cut-off mechanism inversely to that of the eccentric, substantially as described.

4. In a steam-motor, in combination with a high-pressure and a low-pressure cylinder, cut-off mechanism for the valves of the high-pressure cylinder, variable cut-off mechanism for the valves of the low-pressure cylinder, a single eccentric for operating both of said cut-off mechanisms, and means for adjusting said eccentric to vary the throw of the cut-off mechanism of the high-pressure cylinder and thereby automatically adjust said variable cut-off mechanism to maintain a uniform cut-off of the valves of the low-pressure cylinder, substantially as described.

5. In a steam-motor, in combination with a high-pressure and a low-pressure cylinder geared to a common drive-shaft, an eccentric mounted on said shaft having straps, a valve-rod for operating the valves of the high-pressure cylinder connected directly to one of said straps, a block slidably mounted on and rotating with said shaft and having an inclined surface and a link connection with said eccentric, means for adjusting said block toward or from the eccentric, whereby to vary the throw thereof, a valve-rod for operating the valves of the low-pressure cylinder, differential cut-off mechanism connecting said latter valve-rod with the other of said eccentric-straps, and means for adjusting the throw of said differential cut-off mechanism inversely to that of said eccentric including a pivoted arm having at its end a roller bearing on the inclined portion of said block, substantially as described.

6. In a steam-motor, in combination with a high-pressure and a low-pressure cylinder geared to a common drive-shaft, an eccentric mounted on said shaft having straps, a valve-rod for the high-pressure cylinder connected directly to one of said straps, a cylindrical block slidably mounted on said shaft to rotate therewith, and having an inclined surface and a link connection with said eccentric, means for adjusting said block toward or from the eccentric to vary the throw thereof, a valve-rod for the low-pressure cylinder, a guide-block, a slotted rock-arm pivotally secured thereto at one end and having its outer end pivotally connected to said latter valve-rod, a crank-arm pivotally mounted on the frame and having a stud working through

said slot, an arm carried by the other of said eccentric-straps and pivotally secured to said stud, and mechanism automatically operated in the adjustment of said block to vary the 5 throw of said rock-arm inversely to that of said eccentric, substantially as described.

7. In a steam-motor, in combination with a high-pressure and a low-pressure cylinder geared to a common drive-shaft, an eccentric 10 mounted on said shaft having straps, a valve-rod for the high-pressure cylinder connected directly to one of said straps, a cylindrical block slidably mounted on said shaft to rotate therewith, and having an inclined surface 15 and a link connection with said eccentric, means for adjusting said block toward or from the eccentric to vary the throw thereof, a valve-rod for the low-pressure cylinder, a guide-block, a slotted rock-arm pivotally secured thereto at one end and having its outer 20 end pivotally connected to said latter valve-rod, a crank-arm pivotally mounted on the frame and having a stud working through said slot, an arm carried by the other of said eccentric-straps and pivotally secured to said 25 stud, a rock-shaft, a curved arm secured thereto and having at its outer end a roller bearing on the inclined surface of said block, a crank-arm on said rock-shaft, an arm connected at one end to said crank-arm and at 30 its other end to said guide-block and a spring connected at one end to the frame of the motor and at its other end to said crank-arm,

the combination operating substantially as and for the purpose described.

8. In a steam-motor, in combination with a cut-off mechanism for a high-pressure cylinder and variable cut-off mechanism for a low-pressure cylinder, a drive-shaft, a single eccentric mounted thereon comprising an eccentric-ring slidably mounted on the shaft and provided with parallel slots, straps on said eccentric-ring connected, respectively, with said cut-off mechanisms, plates keyed on said shaft on opposite sides of said eccentric-ring and having studs engaging in the slots thereof, a cylindrical block slidably mounted on said shaft to rotate therewith, a link pivotally connected at opposite ends to said eccentric-ring and said block, respectively, means for adjusting said block toward or from the eccentric to raise or lower said ring and vary the throw of the eccentric, and mechanism cooperating with said block in the adjustment thereof to automatically adjust the throw of said variable cut-off mechanism inversely to the throw of said eccentric, substantially as and for the purpose described.

In testimony whereof I have hereunto set my hand in presence of two subscribing witnesses.

FRANK W. WATERMAN.
